(57) **CLAIM**

I claim the ornamental designs for a lighting fixture, as shown and described.

DESCRIPTION

FIG. 1 is a perspective view of a lighting fixture. This fixture has mirror image symmetry (one hundred eighty degree over-

all rotational symmetry, and mirror image symmetry along a first vertical imaginary plane and also mirror image symmetry along a second vertical imaginary plane, with the first and second vertical imaginary planes being orthogonal to each other).

FIG. 2 is a top view of the lighting fixture of FIG. 1.

FIG. 3 is a perspective view of a lighting fixture. This fixture has mirror image symmetry (one hundred eighty degree overall rotational symmetry, and mirror image symmetry along a first vertical imaginary plane and also mirror image symmetry along a second vertical imaginary plane, with the first and second vertical imaginary planes being orthogonal to each other).

FIG. 4 is a top view of the lighting fixture of FIG. 3. The broken lines shown on the drawings depict environment only and form no part of the claimed design.
